UNITED STATES PATENT OFFICE.

ELMER HARROLD, OF LEETONIA, OHIO, ASSIGNOR TO THE CRESCENT MACHINE COMPANY, OF LEETONIA, OHIO.

ROTARY CUTTER-HEAD.

1,153,910.

Specification of Letters Patent. Patented Sept. 21, 1915.

Application filed April 11, 1910. Serial No. 554,765.

To all whom it may concern:

Be it known that I, ELMER HARROLD, a citizen of the United States, residing at Leetonia, in the county of Columbiana and State of Ohio, have invented certain new and useful Improvements in Rotary Cutter-Heads, of which the following is a specification.

This invention relates to the subject of 10 wood-working machinery, and more particularly to rotary cutter heads for jointers, planers, and similar woodworking machines.

To this end the invention primarily has in view the provision of simple and practical means for securing the cutter blades in 15 place in the head or body, said means not only securely holding the blades, but being also itself held against accidental displacement.

20 In carrying out this general object, the invention particularly contemplates an advantageous improvement in the construction of the fastening means disclosed in, and covered by, my former Patent No. 943,540, dated December 14, 1909. In this connection, the 25 present invention is intended to provide a construction which secures all of the important and practical advantages of the construction set forth in the former patent 30 aforesaid, while at the same time affording means whereby the holding bar or throat piece may be readily and bodily removed from its socket, after the knife blade has been removed, without drawing said throat 35 piece or holding bar lengthwise out of its socket from one end of the cutter head or body, as is necessary in the construction disclosed in said former patent.

With these and other objects in view, 40 which will more readily appear to those familiar with the art as the nature of the invention is better understood, the same consists in the novel construction, combination, and arrangement of parts hereinafter more fully described, illustrated, and claimed.

In the accompanying drawings: Figure 1 is a view in elevation of a head or rotary cutter embodying the present invention. Fig. 2 is an end view partially in section on 45 the line 2-2 of Fig. 1. Fig. 3 is a detail sectional view, and projected end view, of one of the clamping wedges. Fig. 4 is a detail end view of the form of throat piece or holding bar employed in carrying out the 50 present embodiment of the invention. Fig.

5 is a detail end view of a form of tool or wrench employed for adjusting the knife blades.

Similar references designate corresponding parts in the several figures of the drawings.

In the embodiment of the invention disclosed in the drawings, the body 6 of the head or cutter is substantially of the usual shape, and has a plurality of knife receiving 60 seats 7, and outwardly tapering sockets 8 communicating with the seats, a plurality of these sockets being associated with each seat throughout the length of the head. Arranged in each seat is a knife blade 9 and a 70 throat piece 10, the latter constituting a holding bar for the knife blade. According to the present embodiment of the invention, the knife blade is of the ordinary form and provided with the outer beveled cutting edge 75. 9^a and is adapted to be held flat against one side wall of its seat 7 by the throat piece or holding bar 10, which latter flatly and solidly bears against one side face of the knife blade throughout the entire area of 80 the latter. Also, according to the embodiment of the invention disclosed herein, the side of the throat piece or holding bar 10 which flatly abuts one side of the knife blade, is plain and unflanged throughout, 85 while at what may be termed the bottom corner of the throat piece farthest from the knife blade, the said throat piece is provided with a longitudinal locking flange 11 which interlocks with a keeper seat or groove 12 90 formed at one bottom corner of the seat 7 which receives the throat piece and the knife blade. When the parts are assembled, this construction serves to lock the throat piece or holding bar against outward displacement, while at the same time permitting the throat piece or holding bar to be 95 readily removed without sliding it endwise from its seat, that is to say, when the fastening is loosened up and the knife blade removed from its seat or socket, the throat piece or holding bar may be pushed laterally sufficiently to disengage the flange 11 from the keeper seat 12, whereupon, the said throat piece or holding bar may be readily 100 lifted bodily from the said seat or socket, thus greatly facilitating the assembling and disassembling of the parts.

In the construction described, it will also be observed that the various elements con- 110

stituting the fastener are rendered more effective and less liable to displacement by having the knife receiving seats disposed substantially tangentially to the axis of the body.

Arranged in each of the sockets 8 is an outwardly tapered wedge block 13 having a threaded bore therethrough, as shown at 14, to receive the thrust screw 15, which is 10 adjustable in said bore and bears against the bottom of the socket. The said thrust screw has an angular recess 16 to receive an actuating tool. In the construction of this tool, the sockets 8 are first drilled into the 15 body, and the seats 7 then milled therein, said seats being disposed tangentially and cutting through the sockets as shown. It will be obvious that when the blade and throat piece are adjusted in the relation 20 above referred to, the same can be securely fastened by turning the thrust screws 15, which will move the wedge blocks outwardly, thus causing the throat piece or holding bar to clamp firmly against the 25 knife blade.

Another feature of the invention resides in making provision for the positive and accurate adjustment of the individual knife blades 9. According to the expedient shown 30 in the drawings, this is simply and effectively accomplished by boring into the body 6 of the head a suitable number of bearing holes 18. These bearing holes 18 pierce the body at substantially right angles to the 35 knife receiving seats 7, and each of the latter has a suitable number of the said holes associated, and in communication, with the same. The bearing holes 18 are preferably 40 of a cylindrical form and are adapted to receive the cylindrical head 19 of an adjusting wrench or implement 20, which carries at the end opposite its head a suitable operating handle 21. The active end of the wrench head 19 is rabbeted to produce a transverse 45 engaging shoulder 22 upon which is seated the inner edge of the knife blade 9 so that by rotating the wrench 20, the said shoulder 22 will exert a lifting action on the knife blade, causing it to be positively and accurately 50 adjusted to the set position determined by the adjustment gage 23 which is also preferably employed as a part of the adjustment means for the knife blades.

Copies of this patent may be obtained for five cents each, by addressing the "Commissioner of Patents, Washington, D. C."

The adjustment gage 23 preferably consists of a crescent shaped rest yoke 24 whose 55 points rest upon the external surface or periphery of the cutter head body 6. This yoke also receives the gage screw 25 held to a set position by a jam nut 26, and the point of said screw is adapted to be arranged over 60 the outer point of the knife blade 9 when the adjusting wrench or implement 20 is employed.

The improvements referred to are susceptible to the modification disclosed in my 65 former patent aforesaid, and from the foregoing, it is thought that the construction, operation, and many advantages of the herein described invention will be apparent to those skilled in the art without further description, and it will be understood that various changes in the size, shape, proportion, and minor details of construction may be resorted to without departing from the spirit, or sacrificing any of the advantages 70 of the invention.

I claim:

1. A cutter head having a longitudinally extending seat, there being a plurality of 80 sockets communicating with each side of said seat, the sockets at one side of the seat extending at an acute angle thereto, while the sockets on the other side extend through the wall of the seat at approximately right angles thereto; substantially as described. 85

2. A cutter head having a longitudinally disposed seat, a knife located in said seat; a keeper for the knife in said seat extending approximately the full length of the knife, there being a plurality of tangential openings extending through the cutter head into 90 said seat at the knife side thereof, said openings being arranged to form bearings for a knife adjusting wrench, means for holding the keeper against the knife throughout approximately the full length thereof to frictionally hold the knife in position while adjusting, said means being also arranged to lock the knife in its adjusted position within the seat; substantially as described. 95

In testimony whereof I hereunto affix my signature in the presence of two witnesses.

ELMER HARROLD.
